D. J. KELLY.
FILTERING APPARATUS.
APPLICATION FILED MAR. 3, 1911.

1,015,961.

Patented Jan. 30, 1912.

UNITED STATES PATENT OFFICE.

DAVID J. KELLY, OF SALT LAKE CITY, UTAH.

FILTERING APPARATUS.

1,015,961.

Specification of Letters Patent. Patented Jan. 30, 1912.

Application filed March 3, 1911. Serial No. 611,967.

To all whom it may concern:

Be it known that I, DAVID J. KELLY, a citizen of the United States, residing at Salt Lake City, in the county of Salt Lake and State of Utah, have invented certain new and useful Improvements in Filtering Apparatus, of which the following is a specification.

This invention which relates to certain new and useful improvements in head closing mechanisms for tanks, has been found of great value when used in connection with the apparatus for separating and filtering slimes for which Letters Patents were here-
10 tofore granted to me as follows: 815,021, March 13, 1906; and 864,308, August 27, 1907, and 865,912, September 10, 1907, granted to me jointly with John M. Callow.

The present invention consists of an im-
20 proved quick locking mechanism employing a toggle-arrangement by which the head of the apparatus may be positively locked or unlocked to close or open the tank; it further consists of the parts and the constructions,
25 arrangements and combinations of parts which I will hereinafter describe and claim.

In the accompanying drawings forming a part of this specification and in which similar reference characters indicate like parts
30 in the several views: Figure 1 is a sectional view of the open end of a pressure tank showing the removable head therefor, and means for locking and unlocking the head. Fig. 2 is an end view showing the head in elevation. Fig. 3 is a detailed plan view partially in section, showing the cranks and toggle-links for operating the removable head. Fig. 4 is a detail in plan and partial section of a means for locking the toggle-
40 links after adjustment.

The apparatus with which I prefer to use the present invention includes a tank, R, which is preferably set on an incline and may have a general cylindrical form, although it may have any other desired suitable cross-sectional shape. This tank has one of its ends, say the latter one, capable of being opened and closed for the purpose of introducing and removing a carrier which
45 contains the filter frames of any well known and proper construction and which frames may follow the general idea of the corresponding frames of my former patents. These frames and carrier form no essential
50 part of the present invention and accordingly they are not shown; the object of mak-

ing the lower head movable is to permit the carrier and its attached frames and the contained matter which has been collected or caked upon the filters during the filtering operation, to be removed to a point outside of the tank so that the caked material may be detached from the frames and the frames cleaned and the carrier returned to the tank for subsequent filtering function. As in my former patents above referred to, the removable head, Q, and the carrier are accurately guided in their in and out movements relatively to the tank by suitable track rails, 10, upon which travel suitable wheels, 70 12, shown in Fig. 2.

Securely fixed around the open end of the crank is a ring, S, which is pierced at suitable points to receive the U-shaped bolts, O, having nuts at their free ends by which they may be secured and adjusted, said ring having also in its face a groove, 13, in which a packing may be contained; a corresponding flange, 14, on the inner face of the locking head, Q, is designed to engage the packing and to form a tight joint between the head and tank as disclosed in my aforesai' patents.

The head, Q, being attached to the filter carrier and movable therewith, it accord-
85 ingly forms the closure for the open end of the tank when the carrier is run back into the tank and the parts are in their operative filtering position. The head is preferably a rigid casting and has on its outer face near the periphery suitable fulcrum lugs, 15, which lugs, are contained between suitable spaced ears, 16, which serve as guides for the outer ends of the radial levers, P, which are slidably mounted between said guides
90 and have curved faces adapted to operate against the fulcrum lugs.

Projecting from the center of the head is a fixed shaft, A, and on this shaft is slidably mounted the adjusting nut, B, the nut being in the form of a sleeve and being threaded on its exterior; on this threaded portion of the nut is mounted the lever spacing collar, C, to which the inner ends of the radial levers, P, are pivotally connected. 105 From this construction, it will be apparent that when the adjusting nut, B, is rotated, it causes the lever spacing collar, C, to move backward or forward and in this manner the tension of the locking head, Q, against the gasket in the groove, 13, formed in the ring casting, S, can be regulated at will.

On the shaft, A, adjacent the adjusting nut, B, is a cross-head, E, having a groove, in which works a split ring, D, which is secured to the adjusting nut. The cross head, E, is slidably mounted on the shaft, but is prevented from rotation thereon through its connections with the toggle-links F F'.

Extending crosswise of the head is a suitable shaft, H, which is mounted in bearings, I and K, said shaft having fixed to it a handle, J, or other suitable means, by which it may be rotated in its bearings. This shaft has fixed to it the spaced crank arms, 15 G G', and to the inner ends of these arms are pivotally connected the toggle-links, F F', whose opposite ends are pivotally connected to the cross-head, E, as shown in Fig. 3.

From the head, Q, projects a bracket or extension, X, Figs. 1 and 4, having a bearing in which the shaft, H, operates and on this shaft adjacent the outer end of this extension is keyed or otherwise fixed a disk, 25 L, having a hole, M, adapted to be engaged by a spring-pressed pin, M', which is slidably mounted in the bracket or extension, K, and has an operating hand piece on its outer end, said pin being adapted to be forced into the hole in the disk when the two are brought into register, which will be when the parts have been moved to bring the toggle-levers, F, on the dead-center when the head is locked.

In order to positively hold the outer ends of the radial levers, P, against the fulcrum bearings, T, when the levers are moved outwardly, as shown by dotted lines in Fig. 1, I may employ some suitable form of 40 spring, V, which construction, however, is substantially disclosed in my former patents.

From the foregoing description it will be apparent that when the shaft, H, is turned the cranks, G G', are moved to cause the toggle-links, F F', to transmit motion to the cross-head, E, and its attachments and to cause these parts to move along the central shaft, A. The movement of the 50 collar, C, to or from the head, Q, causes the outer ends of the radial locking levers, P, to engage or disengage the U-bolts, O, thus locking or unlocking the head. This movement is accomplished by a simple manipulation of the hand lever and the intermediate connections.

The cranks and toggle-levers cause the forward or backward movement of the lever-spacing collar, C, and its attachment, according to the direction of rotation of the hand-lever, J, which mechanism takes the place of the hand-operated nut on the central screw as shown in my previous patent, and the advantages of the present improvement will be apparent from the

stand point of rapidity and convenience in manipulation.

It will also be observed that the cranks, G G', and toggle-levers, F F', exert the greater power at a point near the dead center as here the velocity of travel is least, therefore, the hand lever has its greater power at the required moment, since the greatest tension comes on the joint between the head, Q, and the ring, S, after the levers, 75 P, have engaged the U-bolts, O.

The cranks, G G', and toggle levers, F F', constitute a mechanism, and the construction of the parts may be varied in general detail and design without departing from the 80 spirit of the invention.

Having thus described my invention what I claim as new and desire to secure by Letters Patent is:—

1. In an apparatus of the character described, the combination with a tank, a removable head forming a closure therefor, said head having a projecting shaft, and a locking mechanism between the tank and head, said mechanism including a freely 85 lengthwise slidable collar on the shaft and radially arranged locking levers carried thereby, of a toggle-mechanism, and connections between the same and said collar for operating the levers and locking and 90 unlocking the head.

2. In an apparatus of the character described, the combination with a tank, a removable head forming a closure therefor, said head having a shaft projecting outwardly from its center, a collar slidable on said shaft, and locking levers carried by the collar and having outer ends engageable with the tank to lock the head to the tank, of a rotatable shaft supported from the 100 head and toggle connections between the same and said collar whereby the head is locked and unlocked during the rotation of said shaft.

3. In an apparatus of the character described, the combination of a tank, a removable head forming a closure for one end thereof, a shaft projecting centrally from the head, an adjusting nut slidably mounted on the shaft, a collar mounted on the adjusting nut, radially-arranged levers having inner ends pivotally connected to the collar, a toggle-mechanism connected with the adjusting nut and moving the collar in and out on the shaft, and means on the 115 tank engaged by the outer ends of said levers for locking the head to the tank, said levers having intermediate portions to fulcrum against the head.

4. The combination with a tank, a removable head forming a closure for one end thereof, a shaft projecting from the head, an adjusting nut slidable on the shaft, a collar threaded on the nut, radially-arranged levers having inner ends pivoted to the col- 125 130

lar, the outer ends of said levers engaging the tank and an intermediate portion of said levers fulcruming against the head for locking the head to the tank, a shaft trans-
5 verse of said head having crank-arms, and a toggle-link connection between said cranks and the adjusting nut, whereby the nut and its attached collar are moved in and out on the first named shaft during the rotation
10 of the cross-shaft to lock and unlock the head.

5. An improved locking head mechanism for pressure tanks, said mechanism comprising the combination with the tank, of a locking head adapted to close the open end thereof, a shaft projecting centrally from the head, an externally threaded nut slidably mounted on said shaft, a collar carried by the threaded nut and movable therewith
15 and adjustable relatively thereto, radially-arranged levers having inner ends pivoted to the collar and having outer portions adapted to fulcrum against the head, locking bolts fixed to and projecting from the
20 tank and engaged by the outer extremities of said levers, a cross-head slidable on the shaft in unison with the adjusting nut, a shaft extending crosswise of the head, crank arms on the second shaft, and toggle-links
25 pivotally connected to the outer ends of the cranks and to said cross head whereby the adjusting nut is moved in and out on the shaft to lock and unlock the head to the tank.
30

35 6. An improved locking head mechanism for pressure tanks, said mechanism comprising the combination with the tank, of a locking head adapted to close the open end thereof, a shaft projecting centrally from the head,
40 an externally threaded nut slidably mounted on said shaft, a collar carried by the threaded nut and movable therewith and adjustable relatively thereto, radially-arranged levers having inner ends pivoted to the col-
45 lar and having outer portions adapted to fulcrum against the head, locking bolts fixed to and projecting from the tank and en-
gaged by the outer extremities of said levers,

a cross-head slidable on the shaft in unison with the adjusting nut, a shaft extending 50 cross-wise of the head, crank-arms on the second shaft, and toggle-links pivotally connected to the outer ends of the cranks and to said cross-head whereby the adjusting nut is moved in and out on the shaft to 55 lock and unlock the head to the tank, and a split ring fixed to the adjusting nut, said cross-head having a groove in which said ring operates.

7. An improved locking-head mechanism 60 for pressure tanks, said mechanism comprising the combination with the tank, of a locking-head adapted to close the open end thereof, a shaft projecting centrally from the head, an externally threaded nut slidably mounted on said shaft, a collar carried by the threaded nut and movable therewith and adjustable relatively thereto, radially-arranged levers having inner ends pivoted to the collar and having outer portions 70 adapted to fulcrum against the head, locking bolts fixed to and projecting from the tank and engaged by the outer extremities of said levers, a cross-head slidable on the shaft in unison with the adjusting nut, a 75 shaft extending cross-wise of the head, crank-arms on the second shaft, and toggle-links pivotally connected to the outer ends of the cranks and to said cross-head whereby the adjusting nut is moved in and out on the 80 shaft to lock and unlock the head to the tank, a disk fixed to the cross shaft having an opening, a bracket extension from the locking head, and a spring-pressed pin in said extension adapted to enter the opening 85 in said disk when the two parts are brought into register whereby the shaft and the toggle connections are locked in their adjusted position.

In testimony whereof I affix my signature 90 in presence of two witnesses.

DAVID J. KELLY.
